HAIR CURLER

Robert Trabish, Chicago, Ill.

Application August 17, 1955, Serial No. 529,010

5 Claims. (Cl. 132—34)

This invention relates to new and useful improvements in hair curling appliances and more particularly to a novel device which automatically, safely and quickly produces pin curls, spiral curls, and ringlets as desired.

The invention embodies a hair winding portion and a handle and actuating mechanism therefor, and is so constructed that the entire device is easily disengaged from a curl immediately after the forming thereof in preparation for use to form other curls. Moreover, since it accomplishes the desired results equally as well when individually used as when it is manipulated by another person, such as a beautician or hair stylist, the invention is adapted for both professional beauty parlor use or use by an individual in the home. Actually, when using the invention, the hair curling operation is so simple that it can be done entirely by feel rather than requiring the use of a mirror as a visual aid.

The hair winding portion comprises means preferably consisting of a cylindrical comb structure adapted to engage and grip a lock of hair, and an idler on which the entire device may be supported as the grip and lock of hair held thereby are spun to form a curl. To turn the grip, an actuating mechanism is provided in the body and handle of the device and attached thereto. Specifically, grip rotation is accomplished by a steep pitched screw and ratchet and pawl arrangement cooperable therewith as the handle is moved inwardly axially into the body; while withdrawal of the handle outwardly from the body disengages the actuating mechanism, leaving the grip free to remain stationary.

Curls and ringlets generally are tediously formed by hand with the aid of combs, pins, and other devices slow to manipulate to achieve the desired effect. Many forms of hairdressing appliances are known to women. Some require the user to wear them for hours before they are effective. Other appliances require the use of heat or chemical solutions for effective results. Repeated usage of them may permanently injure the scalp or hair. Still other hair curling devices have sharp edges and projections likely to cut the scalp of the user as the hair is being set. Many other curling devices are expensive and complicated, requiring that they be used only by specialists; while others, because of their many working parts, easily are subject to misalignment and breakage. And, those devices which are presently known to form curls and ringlets are time consuming to use, and more often than not produce inferior results.

Accordingly, it is an object of this invention to overcome these and other failings of prior known hair curling devices.

It is a principal object of the invention to provide a simple to use and highly efficient hair curling device which produces curls and ringlets with a minimum of effort and in a minimum of time.

Another object of this invention is to provide a rotatable hair grip and hair curling head, and further to provide actuating mechanism therefor effective to turn the

curling head upon application of only a slight pressure thereon.

Still another object of this invention is to provide a device for professional use and for individual use, and which readily engages and grips the hair to thereafter almost automatically produce curls or ringlets as desired.

And still another object of this invention is to produce a hair curling device which is inexpensive to manufacture, strong and durable in use, and easy to manipulate; and to this end it consists of the novel elements and combination of elements hereinafter described and defined in the claims.

The foregoing and other objects, advantages and features of construction will become apparent from a consideration of the following description and the appended drawings.

In the drawings:

Figure 1 is a perspective view of the invention in operative position;

Figure 2 is a cross-sectional view taken on lines 2—2 in Figure 1, showing the operating mechanism in extended position;

Figure 3 is a view similar to that shown in Figure 2, but showing the operating mechanism after the curling head has been spun;

Figure 4 is a view similar to those shown in Figures 2 and 3, showing the operating mechanism after the release thereof for return to extended position;

Figure 5 is a view taken on lines 5—5 in Figure 3; and

Figure 6 is a view showing the cooperating ratchet and pawl mechanism for controlling the curling head.

The herein disclosed device comprises three principal portions; namely, the curling head, a cylindrical body wherein the head is held for rotation relative thereto, and a handle and actuating mechanism for rotating the curling head.

Referring to the drawings, the curling head 10 includes a hollow cylindrical body 11, one end 12 of which has teeth 13 and cutout portions 14 alternatively provided about its cylindrical circumference, and forming an annular comb for engaging and holding the hair during the curling operation. Adjacent its other end of the cylindrical body 11 is formed into a chamber 15 having an enclosure member 16 and a capping member 17.

40 The enclosure member is provided with a central aperture 18 through which an idler stem 19 slidably passes into chamber 15. Within the chamber the idler stem 19 is provided with a gear 20 having teeth 21 adapted to engage teeth 22 provided on enclosure member 16 when the idler 19 is moved outwardly with respect to cylindrical body 11. Capping member 17 and a collar 23 limit the relative movement between the idler stem 19 and cylindrical body 11, while a button 24 on the outer end of the stem provides a convenient and comfortable base for 45 engaging the head during the curling operation.

The body of the curling device comprises a cylindrical housing 25 having an axial bore 26. One end 27 of the housing is of sufficient size to rotatably receive the inner end 28 of curling head 10. At its other end 29, housing

50 25 is adapted to slidably receive the handle and curler actuating mechanism 30 hereinafter described in detail. A helical spring 31, mounted concentrically within housing 25 and against capping member 17, urges the handle and curler actuating mechanism 30 outwardly to the extended position shown in Figure 2.

55 The handle and actuating mechanism comprises a cylindrical piston 32, preferably enlarged at the outer end to provide a convenient handle portion 33, and having an axial bore 34 extending therethrough. An annular retaining shoulder 35, engageable with the end 36 of housing 25, limits the axial movement of piston 32 to within the housing.

At the inner end of the handle mechanism, bore 34 is enlarged to form a cylindrical chamber 37 defined at one end by a wall 38 and at the other end by a cover wall 39. Wall 39 has a central opening 40 aligned with and corresponding to bore 34, while a concentrically appended portion 41 has a similarly aligned axial bore 42.

A steep pitched screw 43, attached at one end 44 within a centrally located slit 45 in capping member 17, provides a shank for turning the curling head 10. Screw 43 extends concentrically through housing 25, spring 31, bore 42, and into chamber 37, wherein the outer end 46 of the screw rests when handle 30 is in the extended position shown in Figure 2.

Within chamber 37 a one way drive mechanism is provided for spinning the curling head 10 as the handle is pushed within housing 25, while allowing the handle to be moved outwardly from housing 25 without turning curling head 10 to its original position. Disposed adjacent to wall 38 and fixed thereto is a ratchet member 47 having teeth 48 and a centrally located hole 49 aligned with bore 34 to allow relative movement of screw 43 through the ratchet. Also located within chamber 37 is a pawl member 50 having teeth 51. The teeth 51 are engageable with the teeth 48 of ratchet 47 when turned in one direction and are slideable over the ramps 52 forming teeth 48 when turned in the opposite direction. Screw 43 passes through a narrow slit 53 in pawl 50, thereby non-rotatably mounting the pawl on the screw yet allowing relative sliding or axial movement therebetween. A slightly compressed spring 54 maintains contact between pawl 50 and ratchet 47.

Rotatable movement of screw 43 relative to bore 34 as the handle is pushed from its extended position, shown in Figure 2, to the position shown in Figure 3, is brought about by the following action. As pressure in the direction of the arrows in Figure 3 is brought on handle 33, the teeth 51 of pawl 50 lockably engage the teeth 48 of fixed ratchet 47. With the teeth 48, 51 so engaged, movement of the handle inwardly is permitted only as the pressure thereon is transmitted through pawl 50 to turn screw 43, thus causing the curling head 10 correspondingly to rotate. At the end of the operating or power stroke, spring 31 is compressed; and upon release of the handle acts on cover 39 to urge the handle outwardly, as shown in Figure 4. During the return movement, the teeth 21 of gear 20 mesh with the teeth 22 of member 16 to prevent even the remote possibility of curling head 10 unwinding. As the handle returns to its outward position the teeth of pawl 50 ride over the ramps 52 forming the teeth 48 on ratchet 47. A piston 55 attached to the outer end 46 of screw 43 guides the screw during its axial travel in bore 42.

The ease of using the invention is well indicated by its simplicity of construction. The hair, if desired, may first be moistened with water or a hair waving lotion. Thereafter, the curling head is approached to the head and the lock of hair to be curled is engaged in the comb grip. Pressure is then applied to the handle 33 to move piston 32 inwardly, causing teeth 48, 51 to lock; while screw 43 rotates curling head 10 to wind the lock of hair held thereby in a tight curl. If the lock to be curled is long, idler 19 is held in the other hand as the curl is formed, and the curling operation is repeated until button 24 may rest against the head upon completion of the curling operation. Reset of the actuating mechanism is accomplished without upsetting the curl so formed, since the ratchet-pawl arrangement allows the handle to be urged outwardly without affecting the curling head. Of course, where the lock of hair is short, button 24 may be rested directly on the head as pressure is applied to the handle to form the desired curl. At the completion of the hair winding operation, the curl is stripped from head 10 by having the fingers hold the curl as the device is withdrawn therefrom. Thereafter the curl or ringlet may be secured in place in the usual manner by a clip or suitable hair pin.

More often than not, however, the device is so effective to produce tight curls that the hair is immediately prepared without the necessity of additional setting time.

Certain modifications are possible without departing from the scope of the invention. For example, spring 31 may be eliminated, since the handle mechanism may be withdrawn by hand as the fingers of the other hand hold housing 25 or idler stem 19.

It also will be understood that the diameter of the curling head determines the size of the curl formed thereby, and that therefore provision may be made for the interchanging of different size heads to achieve curls of various sizes. Moreover, screw 43 may be either a left-hand or right-hand screw to achieve either clockwise or counterclockwise curls.

It is preferred to construct the invention of synthetic plastics, and it is apparent that this preferred material is well adapted to mass production by utilizing well known processes. Such materials are pleasing in appearance, easy to clean, and inexpensive to produce.

While the invention has been described in a specific form and as operating in a specific manner for the purpose of illustration, it is to be understood that the invention is not limited thereto, since various modifications will suggest themselves to those skilled in the art without departing from the spirit of the invention, the scope of which is set forth in the annexed claims.

I claim:

1. A hair curling device comprising an annular housing; an axially bored handle slidably movable into one end of said housing; a chamber carried at the inner end of said handle; a steep pitched screw extending through said housing and said chamber and rotatable therein; ratchet means within said chamber and cooperable with said screw for compelling rotation thereof as said handle moves inwardly towards said housing and for releasing said screw as said handle moves outwardly from said housing; a spring anchored in said housing urging said handle outwardly therefrom; a curling head mounted in the other end of said housing, attached to said screw, and rotatable therewith; an annular comb extending around the outer end of said curling head to grip the free end of the lock of hair to be curled; and an idler stem freely rotatably attached to said curling head and extending axially therebeyond for supporting said device during the hair-curling operation.

2. A hair curling device comprising a steep pitched screw, a handle movable axially relative to said screw, a chamber at one end of said handle, ratchet means in said chamber cooperable with said screw for compelling rotation thereof as said handle is moved axially relative thereto in a first direction and for releasing said screw as said handle is moved in a direction opposite to said first direction, a curling head carried by said screw and rotatable therewith, an annular comb extending around an end of said curling head to grip the lock of hair to be curled, and an idler freely rotatably attached to said curling head and extending axially therebeyond for supporting said device during the hair curling operation.

3. A hair curling device comprising a housing; a steep pitched screw extending through said housing; a handle moveable parallel to the axis of said screw; ratchet means carried by said handle, said ratchet means being cooperable with said screw for compelling rotation thereof as said handle is moved in a first direction and for releasing rotational restraint on said screw as said handle is moved in a direction opposite to said first direction; a curling head connected with said screw for rotation therewith, means forming part of said head to engage and grip the lock of hair to be curled, and a stem connected with said head and extending therebeyond for supporting the device during the curling operation.

4. A hair curling device comprising a housing, a steep pitched screw extending through said housing, ratchet means adjacent one end of said housing, said ratchet

means being cooperable with said screw for compelling rotation thereof as pressure is brought axially upon said screw in a first direction and for releasing rotational compulsion on said screw as pressure is brought axially thereon in a direction opposite to that of said first direction; a curling head attached to said screw for rotation therewith; means on said curling head to engage a lock of hair thereon for turning therewith; and idler means connected with said curling head and freely rotatable relative thereto.

5. The hair curling device described in claim 1 wherein said idler stem is movable longitudinally with respect to said curling head and has sufficient length to be gripped for holding said device, and additionally including retaining teeth carried by said curling head; and locking

10

5

teeth carried by said idler stem, non-engageable with said retaining teeth as said handle moves inwardly, and cooperable with said retaining teeth to lock said curling head and said idler stem, as said idler stem is held and the handle is urged outwardly, thereby preventing unwinding of said curling head and the curl formed thereon.
